UNITED STATES PATENT OFFICE.

OSCAR H. PIEPER AND ALPHONSE F. PIEPER, OF ROCHESTER, NEW YORK.

DENTAL ENGINE-BRACKET.

1,111,177.

Specification of Letters Patent. Patented Sept. 22, 1914.

Application filed May 27, 1912. Serial No. 699,939.

To all whom it may concern:

Be it known that we, OSCAR H. PIEPER and ALPHONSE F. PIEPER, both of Rochester, in the county of Monroe and State of New York, have invented certain new and useful Improvements in Dental Engine-Brackets; and we do hereby declare the following to be a full, clear, and exact description of the same, reference being had to the accompanying drawings, forming a part of this specification, and to the reference-numerals marked thereon.

The present invention has for its object to afford an improved construction in dental engine brackets, and relates to the type of bracket embodying, generally, a horizontal supporting arm for the motor, the supporting arm being mounted for upward or downward movement to adjust the motor to any desired position.

The invention further contemplates the provision of a novel construction and arrangement of parts which enables a more ready adjustment, and also permits the supporting arm to be extended laterally and to be effectually supported in any position of adjustment.

To these and other ends the invention consists in certain improvements and combinations of parts all as will be hereinafter more fully described, the novel features being pointed out in the claims at the end of the specification.

In the drawings: Figure 1 is a view in side elevation of a dental engine bracket, embodying a preferred arrangement of parts, according to the present invention; Fig. 2 is a sectional view on the line 2¹—2^a of Fig. 1; Fig. 3 is a vertical sectional view on the line 3¹—3^a of Fig. 1; Fig. 4 is a vertical sectional view through a portion of the motor; Fig. 5 is a partial enlarged elevation, with parts in section, of the bracket; Fig. 6 is an enlarged elevation, partly in section, of the outer end 45 of the supporting arm, and constituting a continuation of Fig. 5; Fig. 7 is a sectional view on the line 7¹—7^a of Fig. 5; Fig. 8 is a sectional view on the line 8¹—8^a of Fig. 7; Fig. 9 is an enlarged sectional view of the upper part of the counterbalance and its connections, and Fig. 10 is a view in side

elevation, showing the supporting arm extended.

Similar reference numerals throughout the several figures indicate the same parts. 55

1 designates a support which is attached in any suitable manner to the wall and is provided with arms 2 which receive the hollow posts 3. Mounted upon the arms 2 is the vertical guide 4 which carries lugs 5 having openings to receive the aforesaid posts 3, whereby the guide is permitted a swinging movement on the support 1. The guide 4 is arranged vertically, as shown, and preferably comprises a track, adapted to receive 60 the carriage on which the supporting arm is arranged. The carriage includes a vertical post or standard 6 provided at its upper and lower ends with wheels 7, preferably mounted on roller bearings, and arranged to engage the walls of the guide, as shown in Fig. 2. The carriage is provided at its lower end with the forwardly projecting portion 8 to which the supporting arm is secured, the latter comprising a stationary 65 tubular member 9 and a movable telescoping member 10 arranged within the stationary member 9, as shown.

In order to properly brace the supporting arm, in any of its adjusted positions, there 80 is provided a flexible device connecting the supporting arm and the carriage, and adapted to maintain the supporting arm when extended. To this end, the carriage is provided at its upper end with a forwardly 85 projecting bifurcated member 11 within which is mounted the pulley 12.

13 is a tube provided at its upper end with arms 14 which are connected to the lower part of the bifurcated member 11, the opposite end of the tube being provided with corresponding arms 15 which are connected to the upstanding lugs 16 arranged at the outer end of the stationary member 9. A 90 flexible device 17, preferably in the form of a wire, is secured at one end to the post 18, arranged at the outer end of the movable member 10. The wire 17 passes thence around the pulley 12, through the tube 13, around a pulley 19 which is pivoted between 95 the lugs 16, and is secured preferably at the inner end of the movable member 10. To 100

accomplish this, the latter carries a projection 20, having a threaded opening to receive a threaded post 21 secured to the end of the wire 17. By this construction, it will be seen that the wire 17 constitutes a brace for the supporting arm in any position, and as the movable telescoping member 10 is moved forwardly, to lengthen the supporting arm, the ends of the wire 17 are correspondingly moved forwardly, thus changing the position of the wire so as to afford a more or less rigid brace between the carriage and the supporting arm at all times.

In order to hold the carriage in any position of vertical adjustment, there is provided a counterbalance, preferably consisting of a weight 22 connected to the carriage in the following manner. Secured at the upper end of the carriage is a laterally extending post 23 to which are attached the ends of a cable or cord 24, as shown in Fig. 7. The strands of the cable 24 pass thence upwardly, over the double pulley 25 which is arranged at the top of the guide, and downwardly to the weight 22, where it passes around a pulley 26. The cable 24 is provided with projections 27, fixed thereto in spaced relation above the weight, as shown in Fig. 9, and arranged beneath said projections is a plate 28 having openings through which the cable passes. By this arrangement, in case either strand of the cable breaks, its projections together with the plate 28, will drop until they engage the pulley 26 and the remaining strand will serve to hold the weight in operative relation until the cable can be repaired.

Arranged at the upper and lower extremities of the vertical guide are spring actuated buffers, preferably consisting of the plungers 29 which are controlled by suitable springs 30, and are adapted to engage the carriage as the latter reaches the limit of its upward or downward movement, to prevent any sudden jar or breaking.

The motor, designated at 31, is suitably suspended at the outer end of the supporting arm.

32 designates a cord passing through the supporting arm, as shown, and containing the leads to the motor. The motor shaft 33 carries pulleys 34 and 35, from which movement is transmitted to the hand piece, as usual in this class of machines. To afford a rotatable support for the hand piece, there is provided a collar 36 which is adjustably secured to the motor casing, and is threaded to receive the annular ring 37.

38 designates a supporting plate arranged on the collar 36 and held in place by the annular ring 37, whereby it may swing to any position relatively to the motor casing.

39 designates a connecting member which may be attached to the supporting plate 38 in any suitable manner, as by means of the

set screw 40, the connecting member 39 being adapted to support the hand piece, which is not shown in the present embodiment, as it constitutes no part of the invention.

70

We claim as our invention:

1. In a dental engine bracket the combination with a motor, of a vertically disposed guide, a supporting arm for the motor, a carriage on which the supporting arm is mounted, said carriage being provided with wheels arranged for movement between the walls of said guide, and a counterbalance connected to the carriage.

75

2. In a dental engine bracket the combination with a motor, of a vertically movable carriage, a supporting arm for the motor mounted on the aforementioned carriage, and a flexible connection between the carriage and the supporting arm.

80

3. In a dental engine bracket, the combination with a motor, of a vertically movable carriage, an extensible supporting arm for the motor mounted on said carriage, and a flexible connection between the carriage and the extensible supporting arm.

85

4. In a dental engine bracket, the combination with a motor, of a vertically movable carriage, an extensible supporting arm for the motor including a movable telescoping member, and a flexible device having its ends connected to said movable member and attached between its ends to the carriage.

90

5. In a dental engine bracket, the combination with a motor, of a vertically movable carriage, an extensible supporting arm for the motor mounted on the carriage and including a movable telescoping member, pulleys arranged on the carriage and on the movable member respectively, and a flexible device passing around said pulleys and having one end fixedly secured at the forward portion of the movable member and the other end adjustably secured at the rear portion of the movable member.

100

6. In a dental engine bracket, the combination with a motor, of a vertically disposed guide, a supporting arm for the motor, a carriage on which the supporting arm is mounted, said carriage being arranged for movement between the walls of said guide, and a counterbalance connected to the carriage.

110

7. In a dental engine bracket, the combination with a motor, of a vertically disposed guide, a supporting arm for the motor, a carriage on which the supporting arm is mounted, said carriage being arranged for movement on the guide, spring buffers disposed at the extremities of the guide and arranged to engage the carriage, and a counterbalance connected to the carriage.

120

8. In a dental engine bracket, the combination with a motor, of a vertically disposed guide, a supporting arm for the motor, a

125

130

carriage on which the supporting arm is mounted, said carriage being arranged for movement on the guide, a counterbalance, and a plurality of connections between the counterbalance and the carriage.

9. In a dental engine bracket, the combination with a motor casing embodying a bearing, a collar adjustably secured on the bearing, securing means having threaded en-

gagement with the collar, and a supporting member surrounding the collar and held in position by the securing means.
